JOHN H. GOETZEL, OF CLEVELAND, AND PAUL C. SMITH, OF LAKWOOD, OHIO

SKATE

Application filed March 21, 1931. Serial No. 524,326.

Our invention is an improvement in skates and relates more particularly to an adjustable clamping device for use therewith.

One of the objects of our invention is to provide means for clamping a skate to the foot of the wearer with greater ease and with more uniform distribution of the clamping forces to the foot wear to which the skate is attached.

Another object of our invention is to construct a skate clamping device by which the skate may be easily and securely attached to athletic shoes or other soft-soled footwear which readily conforms to the contour of the foot of the wearer.

Another object of the invention resides in a novel clamping device wherein the clamping members may be adjusted simultaneously to the shoe of the wearer by a single operating mechanism, yet which is so constructed that self adjustment of each of the members lengthwise of the skate is likewise obtainable.

Other objects and advantages of our invention will become apparent from the following description of an embodiment thereof illustrated in the accompanying drawing in which like reference characters are employed to designate like parts throughout the same.

In the drawing:

Figure 1 is a bottom plan view illustrating one form of our invention, and,

Figure 2 is a fragmentary side elevation of the same.

Referring to the drawing in detail, the reference numeral 1 indicates the foot plate, which is formed to the general contour of a foot, the rear of the plate is formed upwardly to provide a heel plate as shown at 2. Slots 3 are provided in opposite sides of the heel plate to allow the insertion of straps.

It will be noted that the side walls of the heel plate are arranged to converge rearwardly and are preferably flat as at 4 to permit easy adjustment of heels of different sizes and shapes.

In the present embodiment of our invention we have shown the same applied to skates employing but two wheels although it is to be understood that this invention is

equally applicable to other forms of skates. In the present embodiment the forward wheel 5 is rotatably mounted in suitable bearings in the wheel support 6. The rear wheel 7 is likewise rotatably mounted in a rear wheel support 8 and is in substantial alignment with the other wheel. The supports 6 and 8 may be formed by stamping from sheet metal and are preferably formed with reinforcing ribs extending lengthwise thereof.

The present invention has to do primarily with an improved clamping means for securing the skate to the foot of the wearer and includes means whereby the jaws of the forward clamp may be adjusted to the foot of the wearer, the said jaws being also self adjustable with respect to the clamp operating means.

In carrying out our invention as illustrated in the accompanying drawing we provide a guide 9 securely fastened to the under side of the foot plate and having portions spaced from the under surface of the foot plate to permit the slide 10 to operate therebetween. The slide carries an internally threaded portion 11 through which is threaded the screw 12, one end of the screw being rotatably carried in the guide 9 the other end of the screw extending rearwardly as a shank and operating in a bearing 12' formed integrally with the rear wheel supporting member. The extreme rear end of the shank 13 of the screw is formed to receive an operating key (not shown).

The slide 10 is provided with an upwardly extending guide pin 14 which operates in a longitudinal slot 15 formed in the foot plate 1. In this manner the slide is restricted to movement longitudinally of the foot plate and is limited in movement in either direction.

The forward end of the slide 10 terminates in an extension 16 to which is pivotally connected a link 17 by means of the pin 18.

Pivotally connected at 27 to the link 17 near the ends thereof are a pair of levers 19 having arcuate slots 20 therein. The levers extend forwardly of the link and are curved outwardly toward the outer ends so as to project beyond the sides of the foot plate 1.

Guide pins 21 project downwardly from the foot plate and operate in the slots 20 of the levers 19. Clamping jaws 22 and 23 are pivotally carried by the projecting ends of the levers 19 respectively. The jaw 22 is adapted to receive an end of a strap (not shown), while the jaw 23 is formed to carry a buckle for receiving the other end of the strap. It is to be understood, however, that the specific types of jaws 22 and 23 shown in the drawing may be removed and gripping jaws substituted therefor in the event that the use of straps is not desired.

The foot plate is provided with strengthening ribs 24 pressed upwardly of the foot plate material forming shallow depressions on the under side of the plate designed to permit free movement of the pins 25 pivotally connecting the jaws to the levers 19. A central longitudinal rib 26 is similarly formed in the foot plate and is in the path of movement of the pin 18 to permit free movement of the head of this pin in the depression formed by the rib.

It will be noted that by providing the link 17, the levers 19 are capable of relative movement substantially longitudinally of the foot plate 1, that is, the link 17 is capable of being rocked about the pin 18. In this manner adjustment of the jaws 22 and 23 may be accomplished independently of the longitudinal adjustment thereof. This is particularly useful in clamping the skate to soft soled athletic shoes or slippers which are flexible and which conform to the foot of the wearer. It often occurs that the foot of the wearer is deformed by bunions or the like which normally extend beyond the contour of the slipper and therefore make proper fitting of the skate difficult. It is to overcome such difficulties as this that the present invention is particularly useful.

In the use of the invention the adjustment is made by applying a key to the shank 13 and turning the key in the proper direction. This results in longitudinal movement of the slide 10 and in an opening or contracting of levers 19 depending upon the direction in which the key is turned. As has been explained before the lateral adjustment of the levers or jaws carried thereby may be accomplished by the longitudinal adjustment of the slide 10 or may be accomplished by rocking the link 17. In the latter case there is a tendency for the levers 19 to shift one way or the other as the clamping jaws are drawn to the sole of the shoe of the user.

It will be seen that our invention is extremely simple in construction and inexpensive to manufacture and that the multiple adjustment may be accomplished by the use of a single key.

Various changes in the details of construction and arrangement of parts may be made without departing from the spirit of our

invention or the scope of the appended claims.

We claim:

1. A device of the class described including a foot plate, a pair of clamping levers slidable thereon, jaws freely pivoted on the free ends of the levers, and means for adjusting the levers laterally of the foot plate, said means comprising a slide being longitudinally movable on said foot plate and having a depending portion internally threaded to receive a screw, a screw extending through the internally threaded portion of the slide and being rotatably mounted at one end in a guide for the said slide, a guide for said slide, a link pivotally mounted intermediate its ends to said slide, the ends of said link being pivotally mounted to the ends of said clamping levers, said levers being relatively movable longitudinally of the foot plate and independently of said adjusting means.

2. In a skate, a foot plate, a pair of clamping levers slidable thereon, freely movable jaws pivoted on the free ends of said levers, and means for adjusting the levers laterally of the foot plate, said means comprising a plate longitudinally movable on said foot plate and having a depending portion internally threaded to receive a screw, a screw extending through the internally threaded portion of the said plate and being rotatably mounted at one end in a guide for said plate, a guide for said movable plate, guide pins depending from said foot plate, said levers having operating slots extending lengthwise thereof to receive said depending pins, a link pivotally mounted intermediate its ends to said movable plate, means extending through the ends of the link for pivotally connecting the same with the inner ends of said respective levers, said levers being relatively movable longitudinally of the foot plate and independently of said adjusting means, said foot plate having portions thereof depressed to form reinforcing ribs on one side of said foot plate and providing channels on the opposite side of said foot plate to receive the said lever and link and pivotal connecting means.

In testimony whereof, we hereunto affix our signatures.

JOHN H. GOETZEL.
PAUL C. SMITH.
